DISPENSER CAP FOR A PRESSURIZED CAN

John Richard Focht, Yonkers, N.Y., assignor to Precision Valve Corporation, Yonkers, N.Y., a corporation of New York

Filed Jan. 18, 1965, Ser. No. 83,489

Term of patent 14 years

(Cl. D58—26)

Fig 5Fig 6Fig 7Fig 8

FIG. 1 is a front perspective view of a dispenser cap for a pressurized can, showing my new design.

FIG. 2 is a perspective view of FIG. 1 turned 180°.

FIG. 3 is a front elevational view.

FIG. 4 is a rear elevational view.

FIG. 5 is a top plan view.

FIG. 6 is an underneath plan view.

FIG. 7 is a side elevational view.

FIG. 8 is a cross-sectional view thereof taken through center of FIG. 7.

I claim:

The ornamental design for a dispenser cap for a pressurized can, as shown.
